UNITED STATES PATENT OFFICE

JOSEPH BEHLE, OF DALLAS, TEXAS, ASSIGNOR TO THE MURRAY COMPANY, OF DALLAS, TEXAS, A CORPORATION OF TEXAS

COTTON FEEDER

Application filed August 24, 1929. Serial No. 388,217.

This invention relates to a cotton feeder, and particularly to a construction such as is generally shown in the patent to W. L. Hancock for cotton gin feeder, No. 1,719,294,

July 2, 1929, wherein the cotton is cleaned during its feeding movement and foreign material collected therefrom discharged by a conveyor.

The cleaning capacity of a machine of this character is much greater than the removing capacity of a single conveyor which is connected to a source of air suction, and if this conveyor becomes overloaded or clogged the efficiency of the machine is materially affected. If any large amount of dirt or refuse collects in the conveyor it is agitated by the blades thereof in feeding toward discharge and rises through the screen into the cotton already cleaned.

This invention has for an object to provide a novel and improved construction including a plurality of conveyors at the lower portion of the cleaner casing geared for joint operation and all delivering at the discharge point for the foreign matter.

A further object of the invention is to present a new arrangement of parallel conveyors having oppositely disposed blades and the shafts thereof directly geared together to effect a feed of both conveyors in the same direction.

Other and further objects and advantages of the invention will be hereinafter set forth and the novel features thereof defined by the appended claims.

In the drawings:

Fig. 1 is a central vertical transverse section,

Fig. 2 is a longitudinal elevation of the lower portion of the cleaner with part in section; and

Figure 3 is a detail end view from the right of Fig. 2.

Like numerals refer to like parts in the several figures of the drawings.

The general construction of the cleaner is shown by the Patent 1,719,294 before mentioned, and comprises the casing 10 having the hopper 11 and feed rollers 12 discharging upon the toothed drum 13. Spaced from

this drum and from the casing is a screen 14 extending at the rear and below the drum, while at the front a discharge chute 15 is provided.

The section of casing at the rear is usually pivoted at 16 upon longitudinal angle irons 17 and 18 to swing upward and outward to permit access to the drum. For the purpose of mounting the screen in spaced relation to the casing, skeleton frames 19 are provided, the screen being secured to a flange 20 at their inner edge and the casing 10 to a flange 21 at their outer edge.

The screen section 22 beneath the drum 13 is carried at the rear by an angle iron 23 and at the front by a similar iron 24 which also spaces the casing of the trough 25 from the screen. The cut-off sheet 26 is supported above the discharge chute by an angle iron 27 and also by ribs 28 extending upward therefrom.

At the base of the dirt trough 25 I have disposed parallel screw conveyors 30 and 31 having right and left spiral blades respectively, the shaft 32 from the screw 30 carries a gear 33 directly meshed with the gear 34 on the shaft 35 of the screw 31. This direct drive is most efficient but causes the rotation of the shafts in opposite directions, and this compensated by the direction of the conveyor 80 blades so that both deliver the dirt into a casing 36 upon a conveyor head 37 at one end of the machine which is usually connected to a source of air suction.

The drive shaft 38 for one conveyor extends through this casing and is provided with the usual drive pulley and belt, as at 39. At the opposite end the conveyor shafts 32 and 35 are mounted in a head 40 which carries a gear cover 41 recessed at its lower end 90 to partially embrace the shafts.

The general operation of the machine is as described in the patent before mentioned upon which this invention is an improvement, and in the practical operation of such a cleaner the amount of dirt and foreign matter collected is much greater than can be efficiently discharged by the dirt conveyor at the base, so that the present invention increases the conveyor capacity and provides for a 100

direct drive of a plurality of conveyors to discharge at the same outlet. The invention also perfects the screen support by utilizing angle irons and a skeleton frame for that purpose.

5 While the specific construction of the several parts has been shown and described, the invention is not confined thereto as changes and alterations may be made without departing from the spirit of the invention as recited in the following claims.

10 What I claim is:—

15 1. In a cotton feeder, a casing, a drum therein, means for feeding cotton thereto, a screen spaced from the drum and casing, a dirt trough beneath the drum having oppositely inclined walls, parallel conveyors in said trough having oppositely disposed blades, feeding from the inclined walls toward the center of the trough, a discharge from all conveyors located at the same end thereof, and means for driving the shafts of said blades in opposite directions.

20 2. In a cotton feeder, the combination of a casing having an inlet hopper and discharge chute, a drum within the casing having means to convey cotton from the hopper to the chute, a curved skeleton frame secured to the casing at the rear of the drum and having lateral flanges at its inner and outer faces, a 25 screen carried by the inner flange of said frame and spaced from the drum, the outer flange of the frame carrying the casing to form a dirt collecting chamber, a dirt trough having inclined walls and communicating 30 with said chamber, a conveyor in said trough, and screen between the drum and trough extending from the conveyor to the discharge chute.

35 3. The combination defined by claim 2, and a cut-off sheet disposed above the discharge chute and extending circumferentially of the drum toward the inlet hopper.

40 4. The combination defined by claim 2, in which the conveyor comprises parallel shafts having oppositely disposed blades feeding from the inclined walls toward the center of the trough, meshing gears on said shafts to drive the same in opposite directions, and a 45 gear cover secured to the casing and depending over said gears.

50 In testimony whereof I affix my signature.

JOSEPH BEHLE.
